US00D510884S

(12) United States Design Patent **(10) Patent No.:** **US D510,884 S**
Sayegh **(45) Date of Patent:** **** Oct. 25, 2005**

**(54) COMPACT ELECTRONIC ARTICLE
SURVEILLANCE DEVICE**

(76) Inventor: **Adel O. Sayegh**, 5134 Paddock Pl.,
Rancho Cucamonga, CA (US) 91737

(**) Term: **14 Years**

(21) Appl. No.: **29/209,676**

(22) Filed: **Jul. 20, 2004**

Related U.S. Application Data

**(62) Division of application No. 29/182,914, filed on Jun. 2,
2003, now Pat. No. Des. 497,320.**

(51) LOC (8) Cl. **10-05**

(52) U.S. Cl. **D10/104; D10/106**

(58) Field of Search **D10/104, 106,
D10/116; 340/571, 572.7-572.9, 573.4;
70/57.1; 24/704.1**
